9 Claims. (Cl. 179—119)

This invention relates to miniature sound transducers, in particular to microphones and earphones used in eye-glass-type hearing aids and behind the ear models.

An object of this invention is to provide a sound transducer substantially smaller in size than the smallest units previously available commercially and having comparable response and sensitivity.

Still another object is to provide such a unit which though extremely small in size is nonetheless relatively easy and inexpensive to fabricate and assemble to the precise tolerances required.

A more specific object is to provide a miniature microphone or earphone which through extremely small is very efficient and reliable.

These and other objects will in part be pointed out in and in part understood from the following description.

The development of ultra-small transistor amplifiers has lead in turn to the development in recent years of hearing aids small enough to be contained in the frames of eyeglasses or spectacles. For many types of hearing loss this style of hearing-aid offers definite advantages over other styles. These advantages include convenience of putting on or taking off, and perhaps more importantly, correct placement of the hearing-aid microphone next to a person's ear where it will more naturally pick up sounds and not be troubled by unwanted noises, such as the crinkling or rubbing of clothing.

One of the main limitations at present with this kind of hearing aid is that the sound transducers, either microphones or earphones, which have been commercially available are very delicate and complicated and though small by other standards are usually the bulkiest elements in the entire unit. The size of these previously available microphones and earphones is such that the spectacle frames housing them have had to be enlarged substantially giving them an unavoidable and undesirable bulbous appearance. The present invention provides a microphone and a companion earphone which are only about half the size of previous units of comparable high performance. The sound transducers provided by the invention contain considerably fewer parts than previous ones and are very efficient and reliable.

In accordance with the invention, in one specific embodiment thereof, there is provided a miniature microphone having a tongue-like armature of magnetic material with one end positioned between two small permanent magnets held by a stationary "U" shaped pole-piece. The other end of the armature is encircled by a stationary electric coil and near the center of the armature is placed a drive pin which extends at right angles to an acoustic diaphragm. These parts are arranged to obtain maximum effectiveness of the magnetic field generated by the magnets. There is very little stray field, and this is further minimized by enclosing the structure in a closely fitting case of magnetic material, such as nickel steel. Because each unit is thus magnetically as well as physically enclosed, the troublesome problem of mutual coupling between a microphone and a closely spaced earphone is effectively eliminated.

The drive pin in this microphone unit is in accordance with an aspect of the invention made readily adjustable in mass so that the frequency response of the unit can be varied as desired in the course of production. As

will appear, other mechanical weight adjustments can also be made. The drive pin is spring-fitted over the armature to give a secure but pivoting connection to it and the other end of the drive pin is cemented to the center part of the diaphragm. The latter comprises a thin flexible sheet of plastic film, such as mylar, cemented along its edges to the rim of the case and having cemented to its center part a reinforcing sheet of thin aluminum. To facilitate the cementing of this plastic layer onto the casing, the layer is initially made larger than necessary so that it overlaps the top edge of the casing. After this layer has been cemented to the edge, the excess plastic material is trimmed off with a razor blade.

The central and major part of the diaphragm behaves as a rigid piston whose vibration under the excitation of impinging sound waves is transmitted through the drive pin to the armature, the motion of which generates in the coil an electric voltage corresponding to the sound waves. The stiffening sheet of aluminum on the diaphragm is uniquely shaped and has a raised circular or oval rib which gives added rigidity and which in conjunction with the plastic film beneath and suitable vent holes serves as a sound transmission tube of considerable length connecting the inside of the case and rear of the diaphragm with the front of the diaphragm and outside. Thus, part of the sound impinging on the front of the diaphragm travels through this tube to the rear side of the diaphragm and, by proper choice of the length of the tube, arrives at the rear in proper phase to reinforce the front sound waves in their action on the diaphragm.

The U-shaped pole-piece of the unit is uniquely mounted in relation to the armature so that the various parts can be readily assembled and then given a final adjustment, made quickly and easily from the outside, to extremely precise tolerances (of the order of a few millionths of an inch). This is done with the unit connected in its actual electrical circuit environment and is accomplished without affecting the acoustic sensitivity of the unit. As a result, quantity production of these units is considerably simplified and much tighter quality control achieved in spite of the fact that these units are only about half the size of previous ones of comparable quality.

The unit just described is made into an earphone simply by modifying the sound transmission tube in the acoustic diaphragm. Now, in an earphone unit it may be desirable to have its frequency response complement that of a companion microphone. Very fine adjustments in this response can be made by varying the weight of the drive pin as was mentioned and also by changing the mass of the diaphragm. A coarser adjustment, as illustrated in a second embodiment of the invention, is obtained by mounting the energizing magnets in the unit on the end of the armature rather than on the fixed U-shaped pole-piece. Additionally, and this arrangement is particularly suitable for a bone conduction type of unit, the electric coil can also be mounted on the armature.

A better understanding of the invention together with a fuller appreciation of its many advantages will best be gained from a study of the following description given in connection with the accompanying drawings wherein:

FIGURE 1 is a perspective view of an eyeglass assembly having a hearing-aid built into the frame;

FIGURE 2 is a greatly-enlarged perspective view of a microphone embodying features of the invention and usable in a hearing-aid as shown in FIGURE 1;

FIGURE 3 is a longitudinal section view taken as indicated by lines 3—3 in FIGURE 2;

FIGURE 4 is an end view taken as indicated by lines 4—4 in FIGURE 2;

FIGURE 5 is a further enlarged view of a portion of the drive pin; and

FIGURE 6 is a view similar to FIGURE 3 but showing an earphone embodying features of the invention.

The eyeglass assembly 10 shown in FIGURE 1 comprises a frame 12 having right and left ear pieces 14 and 16 adapted to fit over a person's ears to hold the frame in place. Mounted within ear piece 14 is a hearing-aid including a microphone 18 and an earphone 20. Extending downward from the latter is a sound-conducting tube 22 whose lower end terminates in a plug 24 adapted to seat within a person's ear canal. The relative size of the microphone and earphone is approximately as indicated. These elements may be mounted and connected to other parts (not shown) of the hearing-aid in conventional fashion.

FIGURE 2 is a greatly enlarged view of the microphone with its casing 26 partly broken away to show the structure inside. This includes an armature having a tongue-like portion 28 extending from the right end of the casing and a base portion 30 extending underneath tongue 28 slightly above the bottom of the casing. The right end of the armature is rigidly supported against the inner vertical end of the casing by a tab 32 welded to the armature at 34 and to the casing at 36. The left end of base 30, see also FIGURE 4, rests upon and is welded to dimples 38 at opposite corners of the casing.

Fastened onto base 30 somewhat to the right of its left end is a U-shaped pole-piece 40 whose legs extend, respectively, above and below the left end of tongue 28. This pole-piece supports the permanent magnets 42 and 44 on opposite sides of the tongue of the armature, the north pole of one magnet facing the south pole of the other, the field generated by the magnets being generally perpendicular to tongue 28. These magnets should be of high efficiency material and preferably should have high A.C. permeability as well. An acceptable material is Alnico V or VI.

The right end of tongue 28 is encircled but not touched by an electric coil 46 which is supported on base 30. The two ends of this coil are connected to terminals 50 and 52 extending through casing 26 and insulated therefrom by an insulator strip 54. Vibration of the tongue in the magnetic field of magnets 42 and 44 generates a corresponding voltage in coil 46, as will be understood by those skilled in the art. The coil 46 signal voltage is then amplified and applied to earphone 20 by conventional amplifier means (not shown) to reproduce the original sound at suitable volume.

Positioned between coil 46 and pole-piece 40 and spring-fitted onto tongue 28 is a drive pin 56 which extends at right angles to an acoustic diaphragm 58. During assembly of these elements, the drive pin is pushed onto the tongue 28 of the armature and grips it (see FIGURE 4) on opposite sides with a jaw-like spring action. This prevents the drive pin from shifting laterally on the armature but permits it to pivot slightly. With the drive pin extending upward from the armature as shown, the diaphragm is then placed on the top edge of the casing and cemented to it, the end of the drive pin extending into a hole 60 in the center of the diaphragm and being joined to it there by a drop of cement which hardens when set.

Diaphragm 58 comprises a thin flexible layer 62 of plastic or similarly performing material, such as .00025 inch thick mylar, whose edges are cemented to casing 26, and a somewhat thicker, stiff layer 64 of metal or the like, such as .002 inch thick aluminum, cemented to it. The side edges of the latter are close to but separated somewhat from the top edge of the casing thereby permitting relatively very free vibration of the rigid center of the diaphragm. The center part of layer 64 is raised in an oval or "race-track" configuration 66 which adds further rigidity to the diaphragm without increasing its weight and which provides a hollow space between metal layer

64 and plastic layer 62. The right end of oval 66 is vented by a front opening 68 through metal layer 64 and the left end is vented by a rear opening 70 through plastic layer 62. Thus a sound transmitting tube comprising two portions of oval 66 in parallel extends from the front to the rear opening. The length of this tube can be varied in production, as desired, by changing the position of openings 68 and 70. To make this tube twice as long, for example, opening 70 can be placed closely adjacent opening 68 with an air seal inside oval 66 in the short length between the openings. Thus, sound will have to travel effectively entirely around oval 66 to go from opening 68 to opening 70. This simple way of adjustment of the length of the sound transmission tube permits considerable adjustment of the frequency response characteristics of the microphone and is a very desirable production aid. The sound transmission tube does not take up valuable space inside casing 26 and it does not complicate fitting or assembly of the parts. It thus represents an important improvement over prior constructions.

The top of the unit is provided with a dished cover 72 which fits snugly onto casing 26 and encloses the diaphragm. The center of the cover is pierced with an opening 78 which permits sound waves to reach the diaphragm.

Pole-piece 40 and the tongue and base portions of the armature provide a generally continuous magnetic loop for the flux produced by magnets 42 and 44. The only air gaps in this circuit are the first one between magnet 42 and the upper side of tongue 28 and the second one between magnet 44 and the lower side of tongue 28, both gaps being relatively short. Now, in order to generate a relatively large voltage in coil 46 for a given up and down movement of tongue 28, which movement may be only a few millionths of an inch, the armature is made of an iron alloy having a very high permeability such as mu metal. Since this material magnetically saturates easily, it is necessary that tongue 28 be adjusted to an at-rest position between magnets 42 and 44 such that the net steady-state flux through it is as low as possible. However, each time mu metal is bent beyond its elastic limit, it loses its desirable magnetic properties, and must be annealed at elevated temperature to regain them. Also, as a practical matter it is impossible during assembly of the unit to position the tongue portion of the armature in exactly the right position between magnets 42 and 44. To permit simple and rapid adjustment of the relative position of tongue 28 while at the same time avoiding the difficulty attendant upon bending mu metal, the portion of the armature base 30 to the left of pole-piece 40, which constitutes an extension 74, is made accessible from outside the casing through a rectangular window 76 (see FIGURE 4) between dimples 38. Thus by inserting a suitable tool below or above extension 74, it can be bent up or down thereby vertically moving pole-piece 40 while tongue 28 remains stationary. This provides a very simple and easy way to "center" the tongue of the armature which, if desired, can be carried out while the microphone is connected in its actual circuit environment. Any direct current which in the circuit would be flowing in coil 46 and which would otherwise cause an unbalanced steady-state flux in the tongue of the armature can thus also be compensated for by this final mechanical adjustment. Since extension 74 is outside the magnetic circuit of the armature, bending it beyond its elastic limit to make this adjustment does not impair the magnetic properties of the armature which, though its base 30 is deflected slightly, is not bent beyond its elastic limit. After the adjustment has been made window 76 is sealed.

Because the reluctance of the magnetic circuit is low, and by virtue of the placement of the armature and pole-piece as shown with magnets on each side of the tongue of the armature, substantially improved efficiency for a given strength of magnet is obtained. This means, conversely, that for a given sensitivity, this unit can be sub-

stantially smaller than previous ones. The stray magnetic field in this unit is small to begin with but it is further reduced by casing 26, which is ferro-magnetic, and which is in contact with the sides of armature base 30 and pole-piece 40. Magnets 42 and 44 are made slightly narrower than casing 26 to avoid direct shunting of their field.

As was mentioned, the weight of the moving mass of the armature can be varied by adjusting the weight of drive pin 56. This is advantageously accomplished, as illustrated in FIGURE 5, by fabricating the drive pin of a thin hard layer 89 of a non-magnetic metal such as beryllium copper plated with a thicker layer 82 of a soft, malleable non-magnetic metal such as silver. Then simply by rolling the softer layer to a desired thickness the weight of the drive pin can be adjusted to a very fine degree. By stamping or blanking it out of a larger strip, the edges of the drive pin will shear away with the softer layer 82 beveled back as indicated at 84 leaving a "knife-edge," formed by the thin hard layer 82, in contact with the armature tongue.

FIGURE 6 shows an earphone 20 similar in construction to microphone 18. Here, sound waves are produced by the vibration of a diaphragm 90 which is identical to diaphragm 58 except that the diaphragm mass is changed and oval track 66 is generally lengthened; also the sound transmission tube is adjusted in length to give the desired bass frequency response. The sound waves so produced are conducted through tube 22 to a person's ear. The moving mass of the tongue of the armature in this embodiment is greatly increased by mounting magnets 42 and 44, and if desired coil 46, on the tongue of the armature. To make this a balanced armature type bone conduction receiver, a further distribution of the masses and stiffnesses allow this transducer to efficiently transfer energy to the mastoid bone behind a person's ear.

An actual microphone substantially identical to microphone 18 which has been built and successfully operated had over-all dimensions of $\frac{1}{4}$ by $\frac{1}{2}$ by $\frac{1}{8}$ inch, contained 13 parts, and had effectively the same sensitivity and response as the smallest known commercially-produced prior unit, which unit contained 23 parts and had dimensions of $\frac{3}{8}$ by $\frac{1}{2}$ by $\frac{1}{8}$ inch. FIGURES 2-4 herein were made from the actual microphone and show the positions and shapes of its various parts in enlarged scale.

The above description of the invention is intended in illustration and not in limitation. Various changes in the embodiment set forth may occur to those skilled in the art and may be made without departing from the spirit or scope of the invention as set forth.

What I claim is:

1. A miniature, high efficiency sound transducer comprising a box-like casing of magnetic material containing a U-shaped armature having one arm adjacent the bottom of said casing and the other arm somewhat above and parallel thereto, the web end of said armature being supported by said casing, a coil encircling a portion of the flux path of said armature near its web end, a U-shaped pole-piece having one arm affixed to the lower arm of said armature and its other arm above the free end of the upper arm of said armature, a pair of permanent magnets mounted on inner portions of said pole piece arms respectively above and below the free end of said upper armature arm, said magnets having relatively high permeability to alternating signal magnetic flux of the transducer and projecting permanent unidirectional magnetic flux directly into said free armature end, a drive pin attached to said upper arm of said armature near its center, and a diaphragm extending across the upper region of said casing, and being attached near its center to said drive pin.

2. A miniature, high efficiency sound transducer comprising a box-like casing containing a U-shaped armature having one arm adjacent the bottom of said casing and the other arm somewhat above and substantially parallel

thereto, the web end of said armature being supported by said casing, a coil encircling a portion of the flux path of said armature near its web end, a U-shaped pole-piece having one arm affixed to the lower arm of said armature and its other arm above the free end of the upper arm of said armature, a pair of permanent magnets mounted respectively above and below the free end of said upper armature arm, a drive pin attached to said upper arm of said armature near its center, a diaphragm extending across the upper region of said casing, and being attached near its center to said drive pin, and wherein said casing is of magnetic material and has walls close to the sides of said pole-piece.

3. A miniature, high efficiency sound transducer comprising a box-like casing containing a U-shaped armature having one arm adjacent the bottom of said casing and the other arm somewhat above and substantially parallel thereto, the web end of said armature being supported by said casing, a coil encircling a portion of the flux path of said armature near its web end, a U-shaped pole-piece having one arm affixed to the lower arm of said armature and its other arm above the free end of the upper arm of said armature, a pair of permanent magnets mounted respectively above and below the free end of said upper armature arm, a drive pin attached to said upper arm of said armature near its center, a diaphragm extending across the upper region of said casing, and being attached near its center to said drive pin, and wherein the lower arm of said armature extends somewhat beyond the end of said pole-piece and is fastened at its outer end to said casing, said end being bendable from outside said casing to adjust the position of the free end of the said other arm of said armature with respect to the arms of said pole-piece.

4. A miniature sound transducer comprising a casing, an armature having a tongue-like portion supported at one end and extending as a cantilever generally parallel to the bottom of said casing, flux means including at least one permanent magnet and a magnetic pole-piece having arms respectively above and below the free end of said tongue-like portion, a coil encircling a portion of the flux path through said armature and having a pair of output terminals, an acoustic diaphragm positioned opposite said armature and supported by said casing, and a drive pin connected between said tongue-like portion and said diaphragm, said armature having a base portion closely along the bottom of said casing, said pole-piece being mounted on said base portion with an extension thereof continuing beyond said pole-piece and accessible from outside of said casing, said armature being of an iron alloy which loses its desirable magnetic properties when bent too much, whereby bending of said extension to position said pole-piece relative to the free end of said tongue-like portion does not affect the magnetic properties of the portions of said armature in the alternating signal flux path of the transducer.

5. The transducer as claimed in claim 4 wherein said pole-piece, armature, magnet and coil are a unitized assembly fastened at one end to said casing wall, said armature extension being fastened at the other end of said casing.

6. An improved electromagnetic sound transducer comprising a tongue-like armature of magnetic material, flux means including a pair of opposed pole faces and a surrounding cup-shaped casing of magnetic material, said pole faces being supported in side edge contact with said casing which also supplies a return path for at least some of the transducer alternating signal flux passing from one pole face to the other, said armature being fixed at one end in said casing and having a movable portion positioned between said pole faces, a small permanent magnet positioned between said pole faces near said armature, said magnet being recessed from contact with said casing, a signal coil encircling a portion of the flux path through said armature, and an acoustic diaphragm stretched over

said casing and connected to said armature to vibrate with it.

7. The transducer as claimed in claim 6 wherein said magnet is fixed to the said movable portion of said armature.

8. A miniature sound transducer comprising a housing of magnetic material, a generally U-shaped armature having two parallel arms, the web region of said armature being fastened to said housing, a pole piece having two opposed faces, said pole piece being fixed to the end region of one of said arms with its said faces on opposite sides of the end region of the other arm, at least one permanent magnet positioned between said faces, said pole piece having its side edges in contact with said housing and said magnet being spaced from contact with said housing to supply a return path for at least some of the transducer alternating signal flux passing from one pole face to the other, a coil encircling a portion of the flux

path through said armature, and a diaphragm mounted over said housing and connected to said armature.

9. The transducer as claimed in claim 8 wherein said magnet is fixed onto the said end region of said other arm of said armature.
